United States Patent Office.

BENJAMIN IRVING, OF NEW YORK, N. Y.

Letters Patent No. 64,324, dated April 30, 1867.

IMPROVED APPARATUS FOR CONCENTRATING THE EXTRACT OF BARK FOR TANNING AND OTHER PURPOSES.

The Schedule referred to in these Letters Patent and making part of the same.

TO ALL WHOM IT MAY CONCERN:

Be it known that I, BENJAMIN IRVING, of the city, county, and State of New York, have invented certain new and useful improvements in Apparatus for Concentrating the Extracts from Bark for Tanning and Other Purposes; and I do hereby declare that the following is a full description of the same.

The nature of my invention consists in constructing a flat worm for distilling purposes, with corrugated plates, whereby is obtained an extensively diffused radiating surface to evaporate the liquids passing through the worm; and the second part of my invention consists in combining with a flat worm made from corrugated plates a steam box or chamber, whereby the operation of evaporating the extract may be carried on; and the third part of my invention consists in combining with a flat worm made from corrugated plates one or more air-tight receiving-tanks for the purpose of obtaining a vacuum in the worm to cause it to be self-feeding and self-discharging, and at the same time carrying off the watery vapors of the extract as disengaged from it while passing through the worm.

But to describe my invention more particularly, I will refer to the accompanying drawings, forming a part of this specification, the same letters of reference whenever they occur referring to like parts.

Figure 1 is a perspective view of the apparatus.

Figure 2 is a longitudinal cut section of the flat worm through the line $x\ x$, fig. 3.

Figure 3 is a transverse cut section of the same through the line $x^2\ x^2$, fig. 2.

Figure 4 is a side view of the flat worm, as arranged between side plates.

Figure 5 is an end view of the flat worm through the line $x^3\ x^3$, fig. 4.

Letter A represents a steam chamber or box, elevated upon a bed-plate or frame, B. In the steam chamber is arranged a flat worm, C, of one or more feet in width, and of any length deemed necessary for evaporating the liquids passing through the worm. The upper and lower sides of the worm are formed of corrugated plates. The object of this is to obtain, first, a greater amount of radiating surface in the worm than would be possible by any other conformation of it; second, to obtain a thin stratum of the liquid in the worm of varying depths, according to the depths of the corrugations in the plates, and thus expedite the elimination of the watery particles of the extract, to obtain a rapid concentration of it; third, to obtain the greatest amount of strength to sustain the pressure upon their broad surfaces while the evaporation is going on. To the upper end of the worm is attached a feed pipe, D, the end of which is inserted into the head of the worm so as to extend across it, and thus, by means of a series of holes in it, diffuse the liquid in a spray over the entire surface of the upper portion of the worm. The lower end of this feed pipe is carried through an exhaust or condensing steam chamber, E, in which a portion of it is formed into a coil for the purpose of taking up the heat of the condensed steam, and thus be partially heated before being discharged into the worm, whilst the end of it thence passes out at the opposite side of the condenser, to connect with and supply the reservoir. Also connected with the upper end of the worm is a pipe, F, for carrying off the watery vapor eliminated from the extract in passing through the worm, the outer or lower end of which is joined upon a pipe, G, connecting two air-tight receiving tanks, H and I, together. To the back side of these tanks is another connecting pipe, J, from about the middle of which projects another pipe, K, to form a connection with the lower end of the worm, to carry off the concentrated extract from the worm to the tanks. These operations are effected by applying any suitable exhausting apparatus to the pipe L and obtaining a vacuum in the tanks. By this means a vacuum is produced in the worm, causing thereby the liquid extract to flow into it through the supply or feed pipe D, and at the same time flow rapidly through it and out by the pipes K and J to the tanks, whilst the watery vapor as fast as liberated from the extract in the worm is carried off by the exhausting apparatus for producing a vacuum in the tanks. To the lower ends of these tanks are faucets, M, for drawing off the concentrated extract, when required. To facilitate this operation faucets, N, are placed in the pipes G and J, so that when drawing off from one tank the vacuum in the other may remain, and thus keep up the continuous operations of the worm. Letter P is a steam pipe attached to the back of the steam chamber for the admission of steam to heat up the worm to carry on the operation of concentrating the extract. To facilitate the circulation of the steam in the chamber and about the worm, holes are punctured in the sides plates of it, between the coils thereof. In practical operations,

however, this will not be necessary, as the worm will be made of a skeleton form, and thus be open on all sides for the free circulation of the steam. Letter R is a pipe attached to the lower part of the steam chamber, for carrying off any condensed waste water in it, and S a gauge or safety-valve to indicate the pressure of steam used for condensing the extract.

Having now described my invention, I will proceed to set forth what I claim, and desire to secure by Letters Patent of the United States:

1. I claim the use of a flat worm made of corrugated sheets or plates of metal, substantially as hereinbefore set forth, and for the purposes described.
2. I also claim, in combination with a flat worm, made substantially as hereinbefore described, a steam chamber or box, for the purposes set forth.
3. I also claim the use of one or more tanks H and I, in combination with connecting pipes G and J and exhausting pipe L, arranged and operating substantially as hereinbefore set forth.
4. I also claim the combination of the flat worm, made as hereinbefore described, with one or more tanks H and I, by means of the pipes F and K, for the purposes hereinbefore set forth.

BENJAMIN IRVING.
